Primary Examiner — Mark A Goodwin*Assistant Examiner* — Harold E Blackwell, II(74) *Attorney, Agent, or Firm* — BEKIARES ELIEZER LLP(57) **CLAIM**

The ornamental design for a tubular container as shown.

DESCRIPTION

FIG. 1 is a front view of a tubular container showing my new design;

FIG. 2 is a top view thereof;

FIG. 3 is a bottom view thereof;

FIG. 4 is a side view thereof;

FIG. 5 is a perspective view thereof;

FIG. 6 is a front view thereof, shown in use; and,

FIG. 7 is a perspective view thereof, shown in use.

The broken lines illustrate portions of the tubular container that do not form a part of the claimed design.

1 Claim, 7 Drawing Sheets(56)
